UNITED STATES PATENT OFFICE.

EUGENE PITOU, OF NEW YORK, N. Y., ASSIGNOR TO AMERICAN SAFETY DEVICE COMPANY, A CORPORATION OF NEW YORK.

SCAFFOLD AND HOISTING MECHANISM THEREFOR.

1,366,487.

Specification of Letters Patent. Patented Jan. 25, 1921.

Application filed June 6, 1917. Serial No. 172,073.

To all whom it may concern:

Be it known that I, EUGENE PITOU, a citizen of the United States, and resident of the borough of Manhattan, in the city, 5 county, and State of New York, have invented certain new and useful Improvements in Scaffolds and Hoisting Mechanism Therefor, of which the following is a specification.

10 The present invention relates to improvements in scaffolds and hoisting mechanism therefor, and more particularly such scaffolds intended for use on buildings of about four or five stories, and which are built up 15 from the ground, as distinguished from scaffolding used in skyscrapers or other high buildings where it is desirable to use suspended scaffolding.

With the old types of built-up scaffolding 20 in use, much delay is occasioned in increasing the height of the same when required, necessitating interference with the work of the brick layers and other workers, and greatly hampering their work. Such scaffolding is furthermore quite expensive, requiring a great amount of lumber, which aside from its own cost, involves other heavy expenses such as trucking, handling and storing.

25 Whenever the scaffold is to be built to a greater height, the planks and working material, such as bricks and mortar, benches, tools, wheel-barrows, etc., have to be shifted to other parts of the building. Because of 30 this great inconvenience, building up of the scaffold is never attempted until it is absolutely impossible for the workmen to continue their work any further, with the result that the workers are required to work in 35 very inconvenient positions, and that they have to continually shift their positions and work upon other sections of the wall, all of these disadvantages contributing to a resultant job, which is neither uniform in appearance, or perfect in structure. The constant loss of time on the part of the workmen amounts to a considerable item in the aggregate, so that the cost of the building 40 is greatly increased.

45 From a safety standpoint, it is notorious that many accidents result from these types of scaffolding as a result of the necessity for constantly shifting the planks and horses and their loose manner of construction. De- 50 livery of material to the workmen is both

slow and inefficient, and because of the constant shifting about, the workmen do not always have a sufficient supply to continue their work properly.

It is an object of the present invention 60 therefore, to provide an improved type of built-up scaffolding, which will eliminate the faults and disadvantages of the old types of scaffolding above referred to, and will operate with a minimum amount of interference with the work, and with a maximum degree of safety, speed and efficiency. With the present invention the workmen will be allowed to constantly continue their work, even during the act of raising the platform. 70 They may always work "bench high," which as is well known, is the most efficient working position, both for the health of the workmen, the amount of work done, and perfection in workmanship. To this end, I 75 propose to provide a scaffolding hoisting mechanism which will support the platform upon uprights, and may be operated to climb the uprights, drawing the scaffolding along therewith. As the platform is raised 80 along the uprights, the uprights below the platform may be reinforced by braces, comparatively few of these being required, and therefore much saving in lumber will be 85 effected.

A further object is to provide such a mechanism as will conveniently operate over splices, and with which the mechanisms upon each upright will be co-operatively connected in such manner as to permit of the 90 support of any portion of a platform by the remaining portions should any particular mechanism become so damaged as to prevent its proper working. I also propose to provide such mechanism as may be operated 95 by one workman, with relatively little effort, and in such manner as to in no way disturb or interfere with the other work, and without the necessity of removing any parts.

A further object is to provide a spacing 100 means that will maintain the uprights in their proper relation despite the great amount of weight suspended therebetween, which would ordinarily tend to collapse or bend the uprights. A further object is to 105 provide flexibility in the hoisting mechanism so that any one hoisting mechanism may be operated properly, while the others are at rest, the platform being literally suspended between the uprights.

With my improved scaffolding, the workmen may continue their work with the greatest amount of efficiency and satisfaction, in that they are not in any way interfered with during the raising of the platform, and as the platform may be raised with convenience at frequent intervals, the workmen may always continue their work in the proper position. As they may always work at one location on the wall, no time is lost in being shifted to another section, and the work will possess a uniformity which could not be obtained under the old methods. Cheaper delivery of bricks, mortar and other working material to the workmen may be effected as the material may be directly delivered from the hoist to the platform at any level without delay, and may be wheeled along the platform directly to the workmen, so that the workmen may always have a sufficient supply of material to work with.

The improved scaffold results in much safer working conditions for the workmen, greatly reducing the chance of accident. It may be quickly set up, and as above pointed out, may be raised at frequent intervals and without the necessity for employing a great amount of additional material, and without interfering with the work. Upon completion of the building, the scaffolding may be quickly and conveniently disassembled.

It is also an object of the invention to make such hoisting mechanism adjustable so that it may be attached to uprights of various sizes, and to provide means for placing an over-head protection above the platform, which will be automatically lifted along with the platform.

With these and other objects in view, embodiments of my invention are shown in the accompanying drawings, and these embodiments will be hereinafter more fully described with reference to the drawings, and the invention will be finally pointed out in the claims.

In the accompanying drawings;

Figure 1 is a side elevation of one of the hoisting mechanisms employed in my improved scaffolding;

Fig. 2 is a front view thereof;

Fig. 3 is a section-plan view along the line 3—3 of Fig. 1;

Figs. 4, 5 and 6 are similar views respectively, along the lines 4—4, 5—5 and 6—6 of Fig. 1;

Fig. 7 is a detail of the ratchet lever employed in operating the hoisting mechanism;

Figs. 8 and 9 are side views showing the manner in which the hoisting device is moved over the splices in the uprights;

Figs. 10 and 11 are side and front views respectively of a modified form of spacer support;

Fig. 12 shows in horizontal section the

manner in which the hoisting mechanism may be attached to an upright of greater dimension;

Figs. 13 and 14 show a slightly modified form of construction in which the shackles may be adjusted to various sizes of uprights; and

Fig. 15 is a perspective view of a scaffold platform embodying my improvements, and illustrating the manner in which the workmen may continue their working uninterrupted during raising of the scaffold, the efficient system of delivery that may be carried out, and the convenience and ease of raising the platform.

Similar reference characters indicate corresponding parts throughout the several figures of the drawings.

Referring to the drawings, and more particularly to Figs. 1 and 2 thereof, the hoisting mechanism employed in my improved scaffolding, and which is merely shown as one illustrative example of my invention, comprises an elongated rack 20, which may be of any suitable length, preferably about five feet long, and substantially square in cross-section, and provided with rack teeth, preferably pitched downwardly, as shown.

At the upper end of the rack 20 there is pivotally secured at the side faces thereof by a bolt 21, a shackle comprising side members 22 and 23 bent inwardly at their forward end into engagement with the side of the rack, the bolt 21 passing through these inwardly bent portions and being secured in place by means of a cotter-pin 24, or other suitable means. The side members 22 and 23 extend at each side of the upright 25, and are connected at the rear of the upright by a bolt 26 passing through oppositely disposed openings 27, the said bolt being secured at its ends by means of nuts 28, and being provided preferably between the side members with a sleeve 29 which engages the surface of the upright. Additional holes 30 are provided in the side members in spaced relation to the holes 27, to permit of the attachment of the shackles to an upright of greater dimensions, as for instance a 6 in. by 4 in. as distinguished from a 4 in. by 4 in.

Intermediate the forward face of the upright and the rack there is provided an automatic wedge or cam mechanism comprising a cam or wedge member 31 mounted upon the squared portion 32 of a shaft 33, extending through openings in the side members 22 and 23. The operating face of the wedge member is eccentric to the shaft 33, being of increasing radius toward the lower extremity thereof, and is provided with a plurality of studs or projections 34 adapted to bite into the upright.

Washers 35 and 36 are provided at each side of the wedge on the shaft 33, and at

- one end of said shaft there is provided a nut 37 for securing the same in place. At the other end there is provided a weighted handle or counter-lever 38 which automatically 5 maintains the wedge in engagement with the upright. It will be seen that any weight directed downwardly upon the rack will cause the wedge member to increasingly bite into the upright and thereby increase the 10 supporting effect of the shackle. An upward movement of the rack, however, releases the wedge from its biting effect upon the upright, and permits the scaffold to climb.
15. The side members of the shackle are maintained in horizontal position by means of stops 39 and 40 upon the sides of the rack, which engage shoulders 41 in the side-members, these shoulders being continuous with 20 an arcuate surface 42 which is concentric to the pivot point 21 of the shackle, and which therefore permits of the swinging upwardly of the shackle upon removal of the bolt 26 at the rear of the upright. This 25 horizontal and pivotal support of the shackle prevents any binding of the same with the upright during its upward movement, and permits of a slight yielding when the weight of the scaffold is supported thereon, and the wedge bites into the wooden 30 upright.
- An upstanding support formed of a pair of strips 43 and 44, riveted together, and twisted centrally as at 45 so that its upper 35 and lower portions are at right angles to each other, is bent outwardly into an inverted U-shape at the lower end and secured over the upper end of the rack 20 by screws 46. The upper end of the support is formed into a U-shaped pocket 47 backed by a plate 48, or other suitable means 40 may be employed, and a bracket is formed thereon, comprising two arms 49 and 50, between which is rotatably supported upon a 45 shaft 51 a roller 52, which engages the upright. The respective ends of a beam 53 are dropped into the pockets 47 of the adjacent hoisting mechanisms, as clearly indicated in Fig. 15, and the beam constitutes 50 a spacer to prevent any bending of the uprights due to the strain of supporting the scaffold. This spacer, as herein-after more fully pointed out, moves upwardly with the hoisting mechanism, and 55 continually performs its function of spacing the uprights. Planking 53^a, canvas or other suitable covering may be supported upon the spacing beams to form an overhead protection.
60. At the lower end of the rack there is pivotally secured by a bolt 54, the upper forked end 55 of a stirrup member 56, preferably formed of two strips of metal riveted together, and at its lower portion bent outwardly and downwardly into two hooks 57 and 58 in which the ends of the putlogs 59 are placed. The stirrup is braced and held against bending by a cross piece 60, secured at its ends to the lower portion of the hooks 57 and 58. The platform planking 61 is 70 supported upon the putlogs, and the end pieces may be cut out as at 62 to embrace the stirrup. A foot-board 63 (Fig. 8) may be dropped behind the stirrup upon the putlogs and a railing may be provided in any suitable manner. The rack and stirrup are maintained at the proper distance from the upright by a roller 64, supported upon a shaft 65 provided between two bracket arms 66 and 67, pivotally supported upon the bolt 80 54, and held in place by nuts 68 provided on the ends of the bolt. The flexibility provided by the pivotal connection between the rack and the stirrup, enables the hoisting mechanism to be operated at one side of the 85 scaffold without operating it at the other side, so that the putlogs may assume an angle other than 90° to the rack.
- A bolt 69, screw threaded at one end, and provided with an eye 70 at the other, is 90 mounted in a passage 71 formed in the stirrup by spreading the strips as at 72, and is held in place by a winged nut 73. A cable 74 is run through the eye of the bolt and extends along the whole length of the scaffold. This forms a safety suspension means 95 for supporting any machine which may become out of order, between the adjacent machines. It will be understood that the bolt may be secured in any suitable manner, as 100 for instance by providing a separate bearing plate attached to the stirrup.
- The means for raising the rack and the platform therewith, consists of a slidable box member 75, disposed upon the rack, extending entirely about the rack at its upper end, and open at its forward portion, exposing the teeth of the rack. The sides of the member 75 are extended forwardly as at 76 and 77, and below the forwardly extending 105 portions, there are provided out-turned portions 78 and 79, the forward faces of which are slightly in advance of the rack teeth. A closure member 80 is secured to the portions 78 and 79 by means of bolts and nuts 81, and 110 extends across the rack, forming with the upper closed end of the box, lower and upper guides for the rack.
- The end portions of the member 80 are bent rearwardly, as at 82 and 83, and form 115 brackets for a lower supporting shackle, comprising side members 84 and 85, pivotally mounted on said end portions by a bolt 86 provided with nuts 87 at its ends for holding the same in place. A spacing sleeve 120 86^a is disposed on the bolt between the said side members.
- The side members 84 and 85 are supported in downwardly inclined position from the upright 25 by means of lugs 88 provided on 125
- 65 130

the inner side of the brackets 82 and 83 at the lower edge thereof, and inwardly of the bolt 86. Thus the members 84 and 85 may be swung upwardly when desired. Additional lugs 89 are provided at the outer side, at the upper edge of the brackets 82 and 83, and outwardly of the bolt 86, and operate similarly to the lugs 88, when the side members are supported on the outer side of the 10 brackets, as illustrated in Fig. 12, when the device is used with an upright of greater width. These outside lugs may, if desired, be in the same position as the lugs 88, but on the outer side of the brackets.

15 The members 84 and 85 extend at each side of the upright, and are connected at the rear in a similar manner to the upper shackle, by means of a bolt 90 passing through oppositely disposed openings 91, 20 and secured at its ends by nuts 92. A sleeve 93 is provided upon the bolt between the side members, which engages the upright, and spaces the side members apart. Additional holes 94 are provided in the side members in spaced relation to the holes 91, to 25 permit of attachment of the shackles to an upright of greater dimensions, as indicated in Fig. 12.

An automatic wedge or cam 95, preferably 30 similar to the cam of the upper shackle, is mounted upon the squared portion 96 of a shaft 97, extending through openings in the side members, washers 98 and 99 being provided at each side of the wedge. A 35 cotter pin 100 is provided at one end of the shaft for securing the same in place, and the other end is bent forwardly as at 101, to form a weighted handle or counter lever, which automatically maintains the wedge in 40 engagement with the upright. The shackle, it will be seen, is permitted to move upwardly freely, but downward movement is prevented by engagement of the wedge with the upright. By throwing the handle upwardly the wedge will be disengaged and 45 the shackle may be moved in either direction.

The forwardly extending portions 76 and 50 77 of the box member 75 are provided respectively with a pair of slots 102, one above the other and inclined downward and inwardly toward the rack. A block 103 provided at its inner face with teeth 104, oppositely disposed to the teeth of the rack, 55 and adapted to fit therein is reciprocatingly mounted between the portions 76 and 77 by means of pairs of pins or lugs 105, provided on the sides of the block and engaging the inclined slots 102. A handle 106 is provided on the outer side of the block which 60 permits of the same being lifted out of engagement with the rack. The block 103 and box 75 form the supporting connection between the shackle and the rack, preventing 65 any downward movement thereof. Upward

movement of the rack is permitted, however, the block being forced upwardly in the inclined slots, falling back into supporting engagement whenever movement of the rack stops. A ratchet toothed pinion 107 is journaled between the side portions 76 and 77, so that its teeth engage the teeth of the rack, the shaft 108 of the pinion being secured at one end by a cotter pin 109, the other projecting end being provided with a squared 70 portion 110, which may be engaged by a ratchet handle 111 (Figs. 7 and 8) to turn the same and thereby raise the rack.

A projecting portion 112 of the block 103 in the rest position of the machine, engages 80 between the uppermost teeth of the pinion, as clearly indicated in Fig. 1. This serves to lock the pinion against turning clockwise, increasing the support of the rack until the rack is moved upwardly by rotation of the 85 pinion in anticlockwise direction under the action of the handle 111, which causes the block to be moved out of engagement with the rack. As the rack is raised, lifting the platform, the rollers 52 and 64 move along 90 the upright, the former spacing the uprights apart, and the latter spacing the rack from the uprights. The cam wedge 31 is released from the upright and the upper shackle moves freely upwardly, the whole support 95 of the scaffold during this upward movement being on the lower shackle. The platform has a certain amount of play with respect to the rack, and is actually suspended between the uprights from the bolts 54. By 100 reason of this fact, and the slidable relation of the cable with the eyelet, one machine may be operated at a time.

In Figs. 8 and 9, I have illustrated the manner in which the machine may be operated across splices in the uprights. These splices generally comprise a pair of boards 113 and 114 nailed across the adjacent ends 110 of two uprights, and engaging the back and one side face thereof.

The bolt 26 is removed from the upper shackle, and the side members 22 and 23 are swung upwardly into substantially vertical position. The rack is then raised until the upper shackle is a considerable distance 115 above the splices, and is then again secured to the upright in supporting position so that the platform may be supported therefrom. The lower shackle is then released from the upright and swung upwardly, and by depressing the ratchet handle 111, the rack is raised sufficiently to permit moving the block 103 out of engagement with the rack, and the box and shackle are manually raised to the upper end of the rack, above the splice, 120 when the shackle is again secured in supporting position, as shown in dotted lines in Fig. 9, whereupon the machine may again be operated to raise the platform. As shown in dotted lines in Fig. 9, the shackle may 125

with the proper adjustment, be swung downwardly.

To normally raise the box and lower shackle to the upper end of the rack after the platform has been raised a distance corresponding to the length of the rack, it is only necessary to free the cam wedge by throwing up the weighted handle, and disengage the block 103 from the rack after the latter has been raised by slightly depressing the ratchet handle 111.

In Figs. 10 and 11, I have illustrated a slightly modified form of spacer supporting means, and in which the same is similar to the support shown in Figs. 1 and 2, but the strips 115 from which the support is formed are not twisted, so that the forked end 116 engages the sides of the upper end of the rack, the transverse portion of the support being sufficiently spaced from the rack to permit swinging of the support upon its pivot 117. With this construction, it will be seen, the support is yieldingly connected to and may be conveniently folded down upon the rack, so that the whole device may be more easily conveyed, and will occupy less space when stored. The stirrup may be folded in a similar manner.

In Figs. 13 and 14, I have shown a slightly modified form of shackle, which may be adjusted to fit uprights of different sizes. In this construction the brackets 118 and 119 of the box member are further spaced apart than in the first described form, and the lugs 120 are of greater length. The side members 121 and 122 are pivotally supported upon a bolt 123, held in place by nuts 124 and 125, and upon the bolt there are provided sleeves 126, 127 and 128, the intermediate sleeve 127 being relatively longer than the end sleeves 126 and 128. When a large upright is used, as for instance a 6 in. by 6 in., all of the sleeves are placed between the side members, as shown in Fig. 13, and the bolt 90 is placed through the holes 94 of the side members. Should a smaller upright be used, as for instance a 4 in. by 4 in. (Fig. 14), the sleeves 126 and 128 are placed at the outer side of the side members, the elongated lugs 120 still serving to support the side members, and prevent downward movement thereof, and the bolt 90 is placed through the holes 91. For a 6 in. by 4 in. upright, it is obvious that in both forms of the device illustrated, it is only necessary to place the bolt 90 in the holes 94.

With my improvements, a very reliable type of scaffold is provided, which is in effect a suspended built-up scaffold. It will be understood, however, that the improvements may be used as an entirely suspended scaffold, by suitably supporting the uprights from overhead outriggers, and if desired the same may be in the form of cables or rods. In this case the cam wedges may be made

of a non-metallic, or other suitable material. The machines may be operated conveniently by one workman without in any way disturbing the other workmen on the platform. The workmen are always permitted to work at the proper height and continuously, so that more work of a better quality will result.

As clearly shown in Fig. 15, the material may be delivered directly to the workmen from the hoist, in sufficient quantities to keep them well supplied, and any suitable form of hoist may be placed on the end or side of the scaffold.

I have illustrated preferred and satisfactory forms of my invention, but it is obvious that changes may be made therein within the spirit and scope thereof, as defined in the appended claims.

I claim:

1. In a scaffold, a plurality of pairs of supports, upper and lower automatic holding members, elongated members connecting said automatic holding members, upper and lower spacing members between said elongated members and said supports, a platform between said supports, and suspension means yieldingly connecting opposite sides of said platform with said automatic holding members and permitting under such connection individual action of said automatic holding members and the lifting of one side independent of the other side.

2. In a scaffold, supports, upper shackles movable on said supports and provided with automatic clutches engaging said supports, lower shackles provided with automatic clutches engaging said supports, rack bars pivotally connected with said shackles, spacers on said rack bars and engaging said supports, boxes mounted on said lower shackles through which said rack bars slide, means carried by said boxes for engaging and disengaging them from said rack bars, a platform, and suspension means flexibly connecting said platform at opposite sides with said rack bars and permitting play therebetween.

3. In a scaffold, a plurality of pairs of supports, upper shackles movable on said supports and provided with automatic cams engaging therewith, lower shackles movable on said supports and provided with cams engaging therewith, guides having pivotal connection with said lower shackles, rack bars slidable in said guides and having pivotal connections with said upper shackles, spacers disposed respectively above and below said shackles and operative to hold said rack bars aloof from and substantially parallel with said supports, independent rack lifting mechanisms carried by said guides, a platform, and suspension means connecting said platform at opposite sides thereof with said rack bars and per-

- mitting play therebetween, whereby said lifting mechanisms may be individually operated and one side of said platform may be raised independently of the other side.
5. In a scaffold, a plurality of pairs of uprights, upper shackles movable on said uprights and provided with automatic cams engaging therewith, lower shackles movable on said uprights, adapted to assume inclined 10 positions with respect thereto and provided with cams engaging therewith, guides having pivotal connections with said lower shackles, rack bars slid able in said guides and having pivotal connection with said upper shackles, spacers disposed above and below said shackles and operative to hold said rack bars aloof from and parallel with said uprights, rack lifting mechanisms carried by said guides, means for holding said upper shackles in horizontal position, and a platform yieldingly connected with said rack bars.
15. An improved hoisting device comprising an elongated member, clutch members carried thereby, and a stirrup pivotally connected at one end of said elongated member and adapted to be folded upon said elongated member when not in use.
20. An improved hoisting device comprising an elongated member, clutch members carried thereby, a stirrup pivotally connected at one end of said elongated member, and a supporting member pivotally connected at the other end of said elongated member, said stirrup and supporting member adapted to be folded upon said elongated member when not in use.
25. In a scaffold, a plurality of pairs of uprights, upper shackles movable on said uprights and provided with automatic cams engaging therewith, lower shackles movable on said uprights, adapted to assume inclined positions with respect thereto and provided with cams engaging therewith, guides having pivotal connections with said lower shackles, rack bars slid able in said guides 30 and having pivotal connection with said up-

per shackles, spacers disposed above and below said shackles and operative to hold said rack bars aloof from and parallel with said uprights, rack lifting mechanisms carried by said guides, means for holding said upper shackles in horizontal position, and a platform yieldingly connected with said rack bars.

35. An improved hoisting device comprising an elongated member, clutch members carried thereby, and a stirrup pivotally connected at one end of said elongated member and adapted to be folded upon said elongated member when not in use.

40. An improved hoisting device comprising an elongated member, clutch members carried thereby, a stirrup pivotally connected at one end of said elongated member, and a supporting member pivotally connected at the other end of said elongated member, said stirrup and supporting member adapted to be folded upon said elongated member when not in use.

45. In testimony, that I claim the foregoing as my invention, I have signed my name in presence of two subscribing witnesses.

50. EUGENE PITOU.
